TURRET ASSEMBLY

James H. Adamsheck, Hiawatha, and Robert J. Rowley, Cedar Rapids, Iowa, assignors to Collins Radio Company, Cedar Rapids, Iowa, a corporation of Iowa
Filed Feb. 26, 1958, Ser. No. 717,781
6 Claims. (Cl. 307—156)

This invention relates in general to crystal turret oven assemblies and more particularly to methods of making such assemblies compact.

In the prior art, piezoelectric crystals used for frequency stabilization have been available in plug-in form. In the forms used, the crystals, however, need a shunting inductance to compensate for the capacitance of the electrodes. Where the crystals are mounted in a standard form, such as in rows on a chassis, the employment of small, variable inductors for compensating the electrode capacitance is feasible. In more compact constructions, such as a turret assembly of plugged-in crystals covered by an oven assembly, the compensating inductances become a very difficult problem; first, in making them small enough and, second, in placing them so that they are compactly arrayed.

Accordingly, it is an object of the invention to provide a crystal turret assembly having compactly arrayed shunting inductances for each of the crystals so mounted.

It is a further object of this invention to provide the functions of switch contact, crystal connector and mounting, and shunting coil in simplified organization.

It is a feature of this invention to provide a connective conductive member comprising a switch contact, a coil form, and a pin receptacle in a single unit and providing a compactness at least equal to the compactness of the piezoelectric crystal mounted therewith.

Further objects, features, and advantages of the invention will become apparent from the following description and claims when read in conjunction with the drawings, in which:

FIGURE 1 shows a sectioned isometric view of the invention incorporated in a crystal turret oven assembly; and

FIGURE 2 shows a section of a conductor used in FIGURE 1.

In FIGURE 1 a crystal turret 10 is mounted for rotation on a shaft 11. The turret comprises a plurality of crystals 12 mounted on the circumference of a circle. These crystals are piezoelectric devices mounted within a metallic shield can and having two relatively rigid pins extending from one end. These pins comprise the electrical circuit connections for the crystal and also serve as mechanical mounting means. The oven assembly comprises a heater coil 14 wrapped around a metallic shield or can 15. Thermostat 16 is mounted on can 15 centrally of the crystals. A disc 17 of thermal insulation material is mounted on the end of the can 15 to reduce thermal losses.

The other end of the turret is constructed around an insulating block 20 which is mounted on shaft 11. An insulating plate 21 is fastened to block 20 and serves as a holder for one end of the conductors or connective members 25 which perform several services as enumerated below. The other ends of the conductors 25 are held by a second insulating plate 22 mounted on the end of block 20 opposite plate 21. Can 15 is fastened to block 20 by means of screws and studs, 23 and 24, respectively.

Shaft 11 is mounted in bearings which permit rotation but provide definite positioning longitudinally. Indexing means and means for rotating the shaft also are provided, as are well known in the art. Similarly, wiper contacts 19, mounted in an insulating block 18, are provided for making the circuit connection between an external circuit,

2

such as an oscillator circuit, and the particular crystal selected by the rotation and indexing of the turret. Plate 13 provides means for a wiper ground connection to the oven while another plate, not illustrated, is used to transfer heating current to the heater coil 14.

As may be readily seen, crystal conductors 25 accept the pins of the crystals in one end 26 and conduct crystal currents through to the switch formed by wiper contact 19 at the other end 27. A shunting inductance 28 is provided which is used to neutralize the electrode capacitance of the crystal. One end of the coil 28 is connected, such as by soldering, directly to conductor 25 mounting the coil. The other end of the coil is brought over to the second conductor, similar to conductor 25 except for the coil and coil form, and connected thereto.

In FIGURE 2, conductor 25 has a pin receiving end 26 and a rounded switch contact end 27. Recess 30, which provides for the accommodation of a crystal pin, is large enough to accommodate a spring 31. Spring 31 provides a firm electrical contact and mechanical support. Mounted on, and concentric with conductor 25, is an insulating coil form 32. Form 32 is a spool-shaped form having the length and height of flange needed to carry the required coil 28. Slots such as 33 are provided in the flanges for holding the ends of the coil.

While the size of the recess 30 in the pin receiving end 26 is dictated by the size of the pin, and the rounded opposite end 27 is made large enough to provide reliable switching characteristics, the length of the conductor 25 may be any length greater than that necessary to accommodate the contact spring 31 or coil form 32, whichever is longer. Conductor 25 is provided with shoulders 34 and 35 which serve to contain the conductor between the mounting plates 21 and 22. A further shoulder 36 serves to retain coil form 32 against plate 21.

In operation or use of the device, the turret is assembled, the crystals 12 are plugged in and the oven cap is assembled over the crystals to heat them and to retain them. Inductance coil 28 is then adjusted as necessary to provide the necessary neutralizing of the electrode capacity of the crystals. The ends of the coil 28 are connected to its pair of conductors 25 in the final assembly, providing the shunting inductance needed.

Rotation of the turret assembly by shaft 11 positions one pair of the conductors 25 under the wiper contacts 19 for circuit connection to the desired crystal. Because the inductances are adjusted for each crystal, the terminals provided by wiper contacts 19 provide a fully compensated switched crystal circuit.

Although this invention has been described with respect to a particular embodiment thereof, it is not to be so limited because changes and modifications may be made therein which are within the full intended scope of the invention as defined by the appended claims.

55 What is claimed is:

1. A selective switching means comprising a housing and at least a pair of wiping contacts, said housing and wiping contacts arranged to move with respect to each other, said housing including a plurality of circuit components and a plurality of connective members constructed and arranged to connect individual ones of said circuit components to said wiping contacts as said housing and wiping contacts are moved with respect to each other, each of said connective members comprising a conductive member having a pin-receiving aperture in a first end thereof, an insulated coil form mounted on said connective member, coil means having two terminals and being wound on said coil form, one of the terminals of said coil means being electrically connected to one of said wiping contacts and the other terminal of said coil means being electrically connected to another wiping contact.

2. A selective switching means in accordance with claim 1, comprising a rotatable shaft and in which said housing comprises a turret-like structure mounted upon said rotatable shaft, and in which the said other ends of said connective members and said wiping contacts are so positioned with respect to each other that at least one of said wiping contacts will make with the other ends of successive ones of said connective members as said turret-like structure is rotated.

3. A selective switching means in accordance with claim 1 in which said housing comprises a turret-like structure and in which said connective elements and said wiping contacts are so positioned with respect to each other that at least one of said wiping contacts will make with the said other ends of successive ones of said connective members as said turret-like structure and said wiping contacts are moved with respect to each other.

4. A selective switching means in accordance with claim 3, comprising spring means arranged within said pin-receiving aperture for firmly holding and for providing good electrical contact with a pin inserted in said aperture.

5. In a selective switching means comprising a housing and a plurality of wiping contacts, said housing and wiping contacts arranged to move with respect to each other, said housing including at least one circuit component, at

least one connective member constructed and arranged to connect said circuit component to one of said wiping contacts as said housing and wiping contacts are moved with respect to each other, said connective member comprising stray capacitance, said connective member further comprising a conductive member having a pin-receiving aperture in one end thereof, an insulated coil form mounted on said conductor, said connective member coil means constructed and arranged to compensate for said stray capacitance, said coil means having two terminals and being wound on said coil form, one of the terminals of said coil means being electrically connected to one of said wiping contacts and the other terminal of said coil means being electrically connected to another wiping contact.

6. A selective switching means in accordance with claim 5, comprising a spring arranged within said pin-receiving aperture for firmly holding and for providing good electrical contact with a pin inserted in said aperture.
